US00D755201S

(12) United States Design Patent
Kim

(10) Patent No.: US D755,201 S
(45) Date of Patent: * May 3, 2016

(54) DISPLAY SCREEN OR PORTION THEREOF
WITH ICON

(71) Applicant: Samsung Electronics Co., Ltd.,
Suwon-si, Gyeonggi-do (KR)

(72) Inventor: Ji-Eun Kim, Suwon-Si (KR)

(73) Assignee: SAMSUNG ELECTRONICS CO., LTD. (KR)

() Term: 14 Years

(21) Appl. No.: 29/489,325

(22) Filed: Apr. 29, 2014

(30) Foreign Application Priority Data

Dec. 30, 2013 (KR) 30-2013-0066505

(51) LOC (10) Cl. 14-04

(52) U.S. Cl.

USPC D14/485

(58) Field of Classification Search

USPC D14/485-488

(57) CLAIM

The ornamental design for a display screen or portion thereof with icon, as shown and described.

DESCRIPTION

FIG. 1 is a front view of a display screen or portion thereof with icon, showing my new design; and,

FIG. 2 is a front view thereof, as shown in a display screen environment.

The broken lines are for environmental purposes only and form no part of the claimed design. The dot-dash broken lines represent unclaimed boundary lines and form no part of the claimed design.

1 Claim, 2 Drawing Sheets
